UNITED STATES PATENT OFFICE.

RUPERT B. DANIELS, OF ADAMS, MASSACHUSETTS.

METHOD AND APPARATUS FOR MAKING PAPER.

Application filed September 16, 1925. Serial No. 56,598.

This invention relates to the art of paper making and pertains more particularly to the making of paper having certain definite portions of thickness different from that of other definite portions thereof.

It is an object of this invention to provide a method and apparatus which shall produce such paper expeditiously and efficiently.

10 Other objects and advantages of the invention will appear hereinafter.

The accompanying drawings illustrate the invention more or less semi-diagrammatically, Figure 1 being a plan view, Figure 2 being a side elevation, certain parts being shown in section to better illustrate the invention, Figure 3 is a detail perspective view, Figure 4 is an enlarged detail view partly broken away, and Figure 20 5 is a section on the line 5—5 of Figure 4.

For purposes of convenience of description the invention has been illustrated as applied to the ordinary Fourdrinier paper making machine in which the stock comprising fibrous material and water is flowed in a liquid state onto a moving wire through which the water is permitted to percolate gradually, leaving the fibrous mass forming the web. In such machines the wire 25 is caused to travel continuously at a uniform rate and the flow of stock onto the wire is ordinarily controlled by slices or bars extending across the path of the wire, said slices being arranged to permit a substantially uniform rate of flow of stock thereunder to form a web of uniform thickness.

According to the present invention, it 40 is proposed to form a web in which the fibrous mass constituting certain defined portions thereof is of a different thickness from that constituting other portions thereof, and this result is accomplished by depositing the stock or pulp to form the web 45 in a layer having different thicknesses at desired different portions thereof. In the present embodiment applied to the Fourdrinier machine it is proposed to control the flow of stock past the usual slices in such manner as to provide a given rate of flow 50 at certain points and to provide a different rate of flow at other points, the web formed by so controlling the flow of the stock having defined portions of different thicknesses.

65 Inasmuch as the web thus formed is still in a more or less fluid state after formation,

it is proposed, in addition, to maintain it in the condition in which formed until sufficient water has been removed therefrom so that there is no tendency for the pulp 60 to flow from one portion to another.

Referring to the drawings, liquid stock from the flow box 1 passes from the flow box over the lip 2 and over the apron 3 onto the wire 4 which passes about the 65 breast roll 4' in the usual manner. As the stock flows along in the direction of the arrows it passes under the first slice 5 which is adjusted with respect to the wire 4 in such manner as to restrict the flow of stock 70 somewhat before passing to the second slice 6. The second slice is arranged somewhat nearer to the wire 4 than the first slice and ordinarily permits the flow of stock 75 thereunder to form a web 7 of uniform 75 thickness.

According to the present invention there are provided at intervals along the second slice means for additionally controlling the flow of stock to form the web such that a 80 different rate of flow is permitted thereunder at these points. In the present embodiment the rate of flow of stock at such points has been controlled to form portions of less thickness than the remainder of the 85 web, this control being effected in the present instance by securing to the second slice an obstruction in the form of a U-shaped plate 8 which may be secured to the slice in any suitable manner. In the present embodiment the plate 8 is bolted to the slice and an elongated slot 9 may be provided in the plate to permit vertical adjustment of the plate and an elongated slot 10 may be provided in the slice to permit lateral 90 adjustment of the plate.

As will be apparent, this obstruction attached to the slice restricts the flow or stock thereunder to a greater extent than along the remainder of the slice, and the web 100 formed beyond the slice, therefore, is of less thickness at this point because a less quantity of fibrous material has been deposited on the wire.

As previously noted, the pulpy mass forming the web is still in a more or less fluid condition after formation by passing under the second slice. Accordingly, it is desirable under certain conditions to maintain the web in the condition in which it is 105 formed to prevent the pulp from the thicker portions of the web from flowing over into

thinner portions to practically obliterate the thinner portions already formed. It has been found that the application of fluid pressure to the thinner portions of the web 5 is effective for this purpose, sufficient pressure being applied to merely prevent the flow of pulp from one area to another it not being sought to accomplish flow by this means. In the present embodiment air 10 under pressure has been used for this purpose and is applied through a pipe 11.

The pipe 11 is provided with a series of openings 12 arranged longitudinally along the under side thereof, and each opening has 15 associated therewith a baffle or deflecting plate 13 to deflect the incoming air current to prevent the direct application thereof to the moist pulp in order to prevent disturbance of the fibers forming the web at this 20 point.

On both sides of the pipe and extending longitudinally thereof throughout substantially its entire length are side walls or curtains 14, comprising in the present embodiment simply flat metal plates secured to the sides of the pipe in any suitable manner.

The pipe 11 is connected to a header 15 through the flexible hose 16 and the header may be connected to a suitable blower or 30 other source of air pressure through the conduit 15'.

Any suitable member of the pipes 11 may be used depending upon the number of portions of less thickness which it may be desired to form in the sheet. One of the pipes 11 for the application of fluid pressure to hold the stock in the condition in which deposited on the wire is provided, of course, for each portion of less thickness.

Each of the pipes 11 may be conveniently supported by the usual cross rods 17 for the deckle frames and may be attached thereto by any suitable means. In the present embodiment means are provided by which the pipes may be adjusted vertically with respect to the cross rods and the wire in order that the pipes may be conveniently brought into proper relationship with the web being formed. Such means may comprise simply threaded bolts 18 passing through the straps supporting the pipes, which bolts may be turned to raise or lower the pipes as desired.

As will be apparent, the pipes 11 with their attached fins or curtains 14 form an elongated hood through which air pressure may be applied to the web in sufficient quantity to prevent inflow of the pulp to the portions of less thickness from the portions of greater thickness. It has been found that desirable results are obtained with the present apparatus when the pipe is so adjusted with respect to the wire and pulp thereon, that the curtains 14 project slightly into the pulp to form a seal to prevent the escape of air 60 along the sides thereof. The curtains 14

should not project too deeply into the pulp for best results, as it has been observed that when this occurs the fibers of the pulp forming the web are sometimes disturbed by a rolling action which takes place between the lower edge of the curtains of the wire which causes undesirable effects in the finished paper.

The forward end of each of the pipes 11 is arranged closely adjacent to the back of the second slice 6 in order that the fluid pressure may be applied to the web immediately after formation thereof, and before the pulp has opportunity to flow from one area to another. In order to better prevent the undesirable flow of pulp immediately back of the second slice where the pulp is still in a very fluid condition, an opening 19 may be provided in the pipe 11 at the forward end thereof through which a current of air may be directed onto the pulp immediately behind the slice. It will be understood, however, that, as in the case of the remainder of the web, the air pressure applied at this point is sufficient only to prevent inflow of pulp and is not sufficient to displace the pulp or to induce flow in the other direction.

The adjustment of the air pressure applied is a matter of some importance, but due to the varying conditions encountered in the manufacturing process, no satisfactory rule as to its amount can be given. Different rates of flow of the stock, different qualities of stock, and even different atmospheric conditions may operate to vary the air pressure required.

The proper pressure may easily be determined by a skilled operator, however, by observance of the apparatus in operation, for the pressure applied should in no case be sufficient to cause the pulp to be extruded beneath the fins 14. In fact, in order to avoid this result with the accompanying undesirable ridge which would be formed thereby on either side of the portion of less thickness, it is preferable to reduce the air pressure to a point where some inflow of pulp may result, as this has no ill effect on the finished paper, although it will be understood that the ideal condition is that in which no flow occurs in either direction.

It is to be understood that the invention may be variously modified and embodied within the scope of the subjoined claims.

I claim as my invention:

1. In a paper making machine, in combination, a Fourdrinier wire, a slice arranged to cooperate therewith to restrict the flow of stock to form a web of desired thickness, means to additionally restrict the flow of stock at designated intervals along said slice to form designated areas of less thickness, and means to apply air pressure to said areas of less thickness, said means including a hood having side walls adapted

to extend into the pulp forming the web to form an air seal.

2. In a paper making machine, in combination, a Fourdrinier wire, a slice arranged to cooperate therewith to restrict the flow of stock to form a web of desired thickness, means to additionally restrict the flow of stock at designated intervals along said slice to form designated areas of less thickness, and means to apply air pressure to said areas of less thickness, said means including a conduit having a plurality of openings distributed along its under side, said conduit being also provided with side walls adapted to extend into the pulp forming the web to form an air seal.

3. In a paper making machine, in combination, a Fourdrinier wire, a slice arranged to cooperate therewith to restrict the flow of stock to form a web of desired thickness, means to additionally restrict the flow of stock at designated intervals along said slice to form designated areas of less thickness, and means to apply air pressure to said areas of less thickness, said means including a conduit having a plurality of openings distributed along its under side, said openings being provided with means for deflecting the incoming air current to prevent the direct application thereof to the web, said conduit being also provided with side walls adapted to extend into the pulp forming the web to form an air seal.

4. In a paper making machine, in combination, a Fourdrinier wire, a slice arranged to cooperate therewith to restrict the flow of stock to form a web of desired thickness, means to additionally restrict the flow of stock at designated intervals along said slice to form designated areas of less thickness, and means to apply air pressure to said areas of less thickness, said means including a hood extending longitudinally of said wire from a point adjacent said slice to a point at which the pulp forming the web is set, said hood being provided with side walls adapted to extend into the pulp forming the web to form an air seal.

5. In a paper making machine, in combination, a Fourdrinier wire, a slice arranged to cooperate therewith to restrict the flow of stock to form a web of desired thickness, means to additionally restrict the flow of stock at designated intervals along said slice to form designated areas of less thickness, and means to apply air pressure to said areas of less thickness, said means in-

cluding a hood extending longitudinally of said wire from a point adjacent said slice to a point at which the pulp forming the web is set, said hood being provided with openings through which air under pressure may be supplied thereto, said openings being provided with means to deflect the incoming air current to prevent the direct application thereof to the web, said hood being also provided with side walls adapted to extend into the pulp forming the web to form an air seal.

6. In a paper making machine, in combination, a Fourdrinier wire, a slice arranged to cooperate therewith to restrict the flow of stock to form a web of desired thickness means to additionally restrict the flow of stock at designated intervals along said slice to form designated areas of less thickness, and means to apply air pressure to said areas of less thickness, said means including a hood extending longitudinally of said wire from a point adjacent said slice to a point at which the pulp forming the web is set, said hood being provided with openings through which air under pressure may be supplied thereto, said openings being provided with means to deflect the incoming air current to prevent the direct application thereof to the web, said hood being provided with an additional opening arranged closely adjacent said slice through which a direct current of air may be directed at the web immediately behind said slice, said hood being also provided with side walls adapted to extend into the pulp forming the web to form an air seal.

7. A method of applying air pressure to a continuously moving web of pulpy material to maintain defined areas of different thicknesses, which consists in applying to the areas of less thickness a confined current of air under pressure, the web itself forming one of the walls confining the air.

8. The method of applying air pressure to a continuously moving web of pulpy material to maintain defined areas of different thicknesses, which consists in applying to the areas of less thickness a confined current of air under pressure, the web itself forming one of the walls confining the air, the air pressure applied being sufficient only to prevent flow of pulp from one area to another.

In testimony whereof, I have signed my name to this specification this 11th day of September, 1925.

RUPERT B. DANIELS.
